TANK FOR STORAGE OF LIQUIDS,
ESPECIALLY HYDROCARBONSAskan Willy Syndergaard, Copenhagen,
DenmarkApplication July 13, 1934, Serial No. 735,042
In Denmark January 6, 1934

6 Claims. (Cl. 220—1)

This invention relates to storage tanks for volatile liquids, such as gasoline or other hydrocarbons, to be stored in the open air.

By the storage of volatile liquids, such as gasoline or other hydrocarbons, in tanks standing in open air (as distinct from being sunk in the ground) it is well known that quite a considerable loss is suffered, due to a portion of the vapors formed in the tank, above the surface of the liquid contained therein, gradually escaping to the atmosphere, either through leaks in the tank or through the breathing holes usually provided in the tank.

A storage receptacle or tank standing in open air is exposed to the direct action of the changing weather conditions and must therefore, especially so far as unavoidable considerable variations of the temperature are concerned, ordinarily be fitted with breathing holes, which holes prevent the occurrence of injurious high or low pressures in the tank owing to the contractions and expansions to which the contents, especially the liquid vapors, of the tank are exposed owing to the unavoidable temperature variations. Thus, for instance, a temperature variation from 15° C. to 30° C. will cause the mixture of air and liquid vapor standing above the surface of the liquid to be expanded by about 10% to 20%, the result being that a corresponding volume of this gaseous mixture will escape by way of the breathing hole or holes of the tank.

When the temperature decreases, the said mixture contracts, and air is then drawn in until the differential pressure is equalized, and during a new increase in temperature, a certain quantity of the mixture of air and vapors will therefore be discharged.

As changes in temperature occur not only from day to night, but often repeatedly within twenty-four hours, for instance, during unstable weather conditions, when the tank is alternately exposed to direct sunshine and shielded from the sun, the loss caused thereby may be quite considerable. Barometrical variations have a similar effect to temperature variations and may under certain conditions cause a quite considerable waste.

In order to remedy the losses due to temperature variations, it has formerly been proposed to cover the top side of the tank and the adjoining part of the vertical walls of the tank with heat-insulating layers, whereby the temperature changes, to which the top side and top part of the walls of the tank are subjected, should be reduced. A coating of the top side of a tank with a heat-insulating layer does not, however,

prevent the remaining part of the tank from being exposed to direct action of the rays of the sun, and in the vapor-filled space of these tanks quite considerable variations are therefore produced, for instance, from day to night. If the liquid surface in the tank is lowered below or essentially below the bottom edge of the heat-insulated top part of the tank, and further even if an iron tank be coated with a heat-insulating layer (which, of necessity, must be relatively thin to be capable of practical application), either on top or all over, there will nevertheless frequently be passed through the insulating layer, for instance, owing to the influence of the sun heat during the daytime, an amount of heat sufficient to cause the temperature of the vapors in the tank to vary approximately between the same ranges as the external temperature.

The object of the present invention is to reduce the loss of liquid, due to evaporation, in a tank erected in the open air and exposed to changing temperature actions by minimizing the temperature variations to which the vapors in the tank are exposed during the most unfavorable external temperature conditions in the course of a certain period of time, for instance, twenty-four hours, a value not exceeding, but preferably being considerably less than, the value of the variations of the temperature of the atmosphere.

To this end, the top as well as the side walls of the metal sheet tank are, according to the invention, fitted with an outer coating or layer of concrete, or of another solid material having a heat-accumulating property of the same order as a layer of concrete. This means that instead of concrete there may be used materials of such kind that an elevation of 1° C. of the temperature of a certain volume of the material requires the supply to the latter of an amount of heat, being of the same order or even higher than the amount of heat which under the same conditions was to be supplied to the same volume of concrete. Such other materials are, for instance, clay, mortar and asphalt. The thickness of the said coating is selected so as to insure that the temperature variations of the vapors in the interior of the tank produced by the external temperature variations are reduced to any desired minimum due to the accumulation of heat in the said material. This layer or coating is hereinafter called the heat-accumulating coating.

In order to keep the thickness of the above-mentioned coating within reasonable limits, it would be suitable, according to a further object

of the invention, to cover the said coating with a second coating prepared from a solid heat-insulating material, i. e., a material which has a low co-efficient of heat conductivity, for instance, a coating consisting of plates prepared from wood fibers. This layer is hereinafter called the heat-insulating layer.

By way of example, it may be mentioned that the variations of the temperature of the vapors in a tank standing in the free atmosphere and made from iron sheet plates having a thickness of 5 mm. may be reduced so as to be less than the change of the temperature in the free atmosphere in the course of twenty-four hours and not to exceed say 5° to 10° C. under the most unfavorable air conditions, if the tank is fitted with an outer coating of reinforced concrete having a thickness of 75 to 125 mm. disposed inside a heat-insulating layer of plates prepared from wood fibers and having a thickness of about 50 mm.

A further object of the invention is to reinforce the tank in such a manner that it will be possible to make it air-tight and sufficiently strong to resist the excess pressure or vacuum produced therein by the maximum temperature variations and barometrical variations likely to occur during the course of, for instance, twenty-four hours.

To this end, the heat-accumulating layer is made from reinforced concrete, with which the top side as well as the side walls of the iron tank are coated.

On the outside of the reinforced concrete the layer of heat-insulating material is disposed, and on the outside of the heat-insulating layer there may be provided, as a protection against humidity and mechanical damage, a water-tight layer of plaster or a coating of galvanized sheet iron or some similar weather-resisting material.

The invention is used in connection with already existing iron tanks as well as for the construction of new tanks. In the last mentioned case iron sheets only 3 or 4 millimetres in thickness may be used instead of the heretofore employed rather heavy iron plates, of which the tank wall proper is consisting, and in that case the reinforcement of an air-tight tank is given such a strength that the same alone will be able to resist the tensile and compressive stresses due partly to the high and low pressures produced in the tank by temperature variations, and partly to variations in the atmospheric pressure, and finally also to the pressure due to the liquid in the tank.

Instead of using the reinforcement as a heat-accumulating medium, the heat-accumulating layer may be a separate coating independent of the reinforcement, and the heat-insulating substance used for this purpose may then be other materials with a high specific heat than just concrete, for instance clay.

The further details of the invention appear from the following description of a tank shown diagrammatically and in vertical section on the drawing.

1 is the interior wall of a tank built of iron sheets, 2 is a layer of reinforced concrete, with which the vertical sides as well as the top side of the tank are covered, and 3 is a heat-insulating layer with which the outside of the concrete layer 2 is covered.

On the outside of the heat-insulating layer 3 there may, if desired, be provided a protective layer 4 of watertight plaster, galvanized iron

sheets or some other weather-resisting material. In the drawing I have shown this layer to be formed of galvanized iron sheets.

If the tank is closed in air-tight manner, then the thickness of the layer of reinforced concrete is selected in such a manner that the heat-accumulating capacity of this layer will be sufficiently high to make sure that the maximum quantity of heat penetrating through the heat-insulating layer 3 and the layer of reinforced concrete under the most unfavorable conditions, during for instance twenty-four hours, cannot produce such a great variation in the temperature of the vapours above the contents of liquid in the tank that dangerous high or low pressures will be produced in the hermetically closed tank. These temperature variations may for instance be reduced so as not to exceed 5 to 10° C., or less than that. It should be noted, however, that the invention is not restricted to the maintenance of temperature variations within these limits. The said variations may be greater or—as mentioned—also smaller. The essential feature is merely that the reinforcement should be constructed in accordance with the selection of the permissible temperature variations, in such a manner that the reinforcement at any time will be able to resist the resulting compressive and tensile stresses. The tank wall 1 may be of a thickness varying from 3 millimetres to one centimetre or more, and the tank has no breathing holes, through which any air or vapours can escape. The reinforcement must therefore be made sufficiently powerful to enable the reinforced tank to resist the high or low pressures produced in consequence of the temperature variations and the variations in the atmospheric pressure.

The tank is fitted with safety valves, not shown, which open themselves if the permissible maximum or minimum pressures in the tank for some reason or other are exceeded. It may further be necessary to provide fire gates in the top side of the tank, which gates open themselves automatically in the case of an explosion.

The bottom 5 of the tank is made for instance for iron and rests, in the construction shown, on a suitable concrete footing. The latter may be heat-insulated on the outside in similar manner as the concrete layer 2. The iron bottom, however, may also rest directly on the ground.

In the construction of new tanks it may be suitable to use the heat-insulating cover 3 as outer forms for the pouring of the concrete layer 2.

If an already existing tank is to be converted into an air-tight tank according to the present invention, reinforcing rods are first to be placed around the vertical sides of the tank, after which the insulating plates 3 are placed into position and held together by means of iron bands encircling the entire tank. The concrete is then deposited between the iron wall 1 and the insulating plates, and the latter are fixed to the concrete by means of hooks or the like, which are previously driven into the plates 3, and project into the space between the latter and the tank wall 1. When the concrete has reached the top edge of the tank, reinforcing rods are deposited on the top side of the latter after any holes in the top side have previously been closed in air-tight manner. On to the top side hooks are welded, which are to be cast into the layer of reinforced concrete subsequently deposited on the top side of the tank, after the same has

previously been supported from the inside by means suitable for the purpose, which means, if desired, can be removed after the concrete has hardened. Finally the insulating plates are deposited, which are to cover the top side of the tank, and these plates are held in position, in the same manner as the insulating plates on the side walls of the tank, by means of hooks or the like projecting into the concrete. Then the insulating plates are suitably, but not necessarily, covered with wire netting and fitted with an external layer of plaster.

10 The procedure in building a new tank is similar, although in such a tank the iron wall may 15 as a rule be constructed of thinner iron sheets than the already existing tanks, and may be assembled by welding instead of by riveting.

20 If the tank is not to be closed in an air-tight manner for instance if ordinary breathing holes are provided in the top of the tank, then it is not necessary to reinforce the concrete coating 25 serving as a heat-accumulating layer. If this layer is prepared from cellular concrete, a separate heat insulating layer may according to circumstances be admitted, because cellular concrete has also heat-insulating properties.

Having now particularly described and ascertained the nature of my invention and in what manner the same is to be performed I declare 30 that what I claim is:—

35 1. A fluid-tight storage tank, comprising a sheet metal receptacle, a layer of concrete on the outer surface of the receptacle, and a heat insulating cover on the outer surface of the said layer of concrete.

2. An air-tight storage tank, comprising a re-

inforced air-tight sheet metal receptacle, a layer of concrete on the outer surface of the walls and top of said receptacle, and a heat insulating cover on the outer surface of the concrete.

3. An air-tight storage tank to be freely 5 mounted in the open, comprising an air-tight sheet metal receptacle, a reinforced outer layer of concrete in direct contact with the wall and top surface of the receptacle, and a heat insulating layer covering the outside of the reinforced 10 concrete.

4. An air-tight storage tank to be freely mounted in the open, comprising an air-tight sheet metal receptacle, a layer of concrete on the outer surface of the said tank, the thickness 15 of the layer of concrete being so chosen that the heat accumulating capacity of the layer is sufficient to limit the maximum variations of the temperature of the vapors in the tank during a certain period of time to a predetermined value 20 being less than the maximum variations of the temperature of the external air during the same period of time and not exceeding 5° C.

5. An air-tight closed tank according to claim 4, on which the outer insulating layer is covered 25 by a layer of material capable of protecting the insulating material against the influence of humidity and mechanical actions.

6. A fluid-tight storage tank comprising a sheet metal receptacle, a layer of material, having a 30 heat-accumulating property of the same order as that of concrete, on the outer surface of the said receptacle, and a heat-insulating cover on the outer surface of the said layer.
